CLAIM

(21) Appl. No.: **29/453,707**

The ornamental design for a mini turbo plane blade with two teeth, as shown and described.

(22) Filed: **May 2, 2013**

DESCRIPTION

(30) **Foreign Application Priority Data**

Apr. 30, 2013 (AU) 201312014

FIG. 1 is a front view of a mini turbo plane blade with two teeth showing my new design;

(51) **LOC (10) Cl.** **15-09**

FIG. 2 is an end view of a mini turbo plane blade with two teeth;

(52) **U.S. Cl.**

FIG. 3 is a cross sectional end view of a mini turbo plane blade with two teeth;

USPC **D15/139**; D15/126

FIG. 4 is a back view of a mini turbo plane blade with two teeth;

(58) **Field of Classification Search**

FIG. 5 is an isometric front view of a mini turbo plane blade with two teeth;

USPC D7/412; D8/16, 70, 71; D15/124, 126,

FIG. 6 is an isometric front/end view of a mini turbo plane

D15/138, 139; 83/589, 663, 676; 144/230;

blade with two teeth; and

407/42, 112-119; 451/548-551

FIG. 7 is an isometric back/end view of a mini turbo plane
